KEY GUIDE

Filed July 27, 1925

FIG. 1.

FIG. 2.

FIG. 4.

FIG. 5.

FIG. 6.

FIG. 3.

INVENTOR
HUGH F. McDONALD
BY
ATTORNEY

UNITED STATES PATENT OFFICE.

HUGH F. McDONALD, OF BURLINGAME, CALIFORNIA.

KEY GUIDE.

Application filed July 27, 1925. Serial No. 46,312.

The present invention relates to key-guides for door-locks and such like, and is designed primarily to assist in the location of key-holes in automobile shift-lever locks, 5 store-window switch-plug locks, and other key-operated locks so positioned as to render uncertain, owing to light conditions or location, the finding of the key-hole and insertion of the key.

10 The device comprises a pendulum-like member provided with a key-retaining notch, or notches, adapted to swing from a pivotal point above the key-hole and so positioned, relative to the key-hole, that, 15 when the device is located by touch and the key placed in one of the notches of the member and swung about its pivotal point, the key is automatically brought into registration with the key-hole and the said member held to position by a properly placed stop 20 awaiting the necessary pressure upon the key for its insertion.

An object of the invention is the provision of a device of the character described that 25 will assist individuals in locating front-door key-holes under poor light conditions, or night-watchmen in readily finding switch-plug key-holes in store-windows, which are ordinarily placed in inconvenient, 30 or out-of-the-way, locations.

A further object is the provision of a key-guide of extremely simple and attractive design and one cheaply stamped from a single piece of metal and readily attachable 35 to a convenient member of the lock-construction.

Other objects and advantages will appear 40 with reference to the subjoined specification and accompanying one sheet of drawings, in which—

Figure 1 is a front elevation, showing an embodiment of my invention as applied to an ordinary door-lock, the full line position of the pendulum-member being substantially the normal position thereof relative to the key-hole, the dot-and-dash position indicating the movement through arc of the pendulum and key necessary to bring the key into registration with the key-hole;

50 Figure 2 is an edge view of the door shown in Figure 1, in which is represented the method of securing the device to the door-lock;

55 Figure 3 is a perspective view of the guide-member shown in Figures 1 and 2; Figure 4 is a front elevation of a Yale-

lock, showing an embodiment of my invention as applied to this form of lock;

Figure 5 is a detail of the embodiment shown in Figure 4; 60

Figure 6 is an edge view of the one shown in Figure 4; and

Figure 7 is a detail of another form of guide-member having two key-engaging notches suitable for use in connection with 65 switch-plug locks.

Referring to the drawings in detail, and to Figures 1 and 2 in particular, my invention, as therein indicated, is shown as applied to an ordinary lock 1, being properly 70 mounted upon the bearing-member 2 thereof directly above the key-hole. The guide-member shown in these views comprises a stamping forming an arm 3 bearing a boss 4 provided with an opening 5 adapted to 75 fit the bearing-member 2 and positioned for oscillatory movement relative to said member as a pivotal point, said arm being provided adjacent its lower end with a key-engaging notch 6 adapted to receive and 80 guide the shank 7 of the key 8 to the key-hole of the lock, the arm 3 being provided at its extremity with a finger-grip 9 positioned for ease of operation by a finger of the left-hand, while the key-shank 7 is held 85 in the notch 6 by the right-hand, the operator maneuvering the arm 3, by means of the right-hand, until the arm has reached the limit of its arcuate swing, as indicated in dot-and-dash lines in Figure 1, in which 90 position it is held by the stop 10 mounted on the escutcheon-plate 11 of the lock, with the notch 6 and key-shank 7 directly in line with the key-hole 12.

The form shown in Figures 4, 5 and 6 95 comprises a semi-circular plate 13 pivotally connected at 14 to a face lock-plate 15 adapted to be limited in its sweep by means of the pin 16, the plate 13 being provided with a notch 17 so positioned as to guide 100 the key 18 to the key-hole 19, when swung to the limit of its arcuate movement by pressure upon the finger-grips 20. The pivot 14 may be sufficiently tight, frictionally, to hold the plate 13 at any pre-determined position, preferably, though, in the normal position shown in full line in Figure 4.

In Figure 7 I have shown a slightly modified form of arm 21 adapted for pivotal connection at 22, this form being designed for 110 use in connection with switch-plug locks, in which construction, one lock is disposed

above the other in close proximity, the notches 23 and 24 being adapted for guidance of a key to either key-hole (not shown) by use of the finger-grips 25.

5 Having thus described my invention, I claim, and desire to secure by Letters Patent of the United States:

10 A key-guide of the character described, comprising, in combination, a door-lock bearing an escutcheon-plate and knob-shank, a guide-member in the form of a stamping having a ring at one end adapted to completely encircle said knob-shank and be dependent therefrom, the said member having 15 a key-engaging notch formed in one edge

adapted to receive and guide the shank of the key and to also normally register with the key-hole of the lock, a stop-pin mounted in the escutcheon-plate immediately adjacent to and slightly above the key-hole and 20 adapted to engage said member to limit its further movement when said notch is brought to register with the key-hole, and a finger grip formed at the lower extremity of said stamping constituted of a portion 25 bent at right angles to the main section of the guide member.

In testimony whereof I have affixed my signature.

HUGH F. McDONALD.
